UNITED STATES PATENT OFFICE.

HIRAM FRITZEN, OF COLUMBUS, NEBRASKA, ASSIGNOR OF ONE-THIRD TO ARLIE F. LYON, OF PLEASANTVILLE, IOWA.

HUSKING MITTEN.

Application filed June 28, 1924. Serial No. 722,957.

To all whom it may concern:

Be it known that I, HIRAM FRITZEN, a citizen of the United States, residing at Columbus, in the county of Platte and State 5 of Nebraska, have invented certain new and useful Improvements in Husking Mittens, of which the following is a specification.

This invention relates to improvements in husking mittens and has as its general object to provide a mitten of this class which will present advantages over the ordinary mitten.

Husking mittens are ordinarily provided with studs or similar roughening elements 15 distributed over the palm of the mitten and over the inner side of the thumb stall, and usually these studs are of some special design and must be produced by special machines thus adding considerably to the cost 20 of manufacture of the particular mitten. It is, therefore, one of the important objects of the present invention to provide such a mitten with a roughened palm and thumb stall surface by the utilization of portions 25 of the material of the mitten and elements which, together with said portions, provide the roughening elements, which first mentioned elements may be purchased upon the market at an exceptionally low cost, thereby 30 enabling the manufacturer to produce a highly serviceable mitten of the class described at a much lower cost than that required in the manufacture of the types of mittens now in use.

Another object of the invention is to provide a mitten which will be ventilated so that it will not be uncomfortable to wear.

In the accompanying drawings:

Figure 1 is a plan view of a left-hand mitten embodying the present invention.

Figure 2 is a similar view of a right-hand mitten embodying the invention.

Figure 3 is a horizontal sectional view on the line 3—3 of Figure 1, looking in the direction indicated by the arrows.

Figure 4 is a detail horizontal sectional view on the line 4—4 of Figure 1, looking in the direction indicated by the arrows.

The mitten will be made in "rights" and "lefts", Figure 1 of the drawings illustrating a left-hand mitten and Figure 2 a right-hand mitten, and as a matter of convenience, like parts in the two views are indicated by corresponding reference numerals, the said numerals in Figure 2 being primed.

The mitten embodying the invention is preferably made from more or less heavy leather and comprises a back section 1, a palm section 2, and thumb stall, indicated by the numeral 3. The back and palm sections are marginally united by stitching to provide a seam 4, and the said margins of the said sections at the sides are preferably substantially parallel, the mitten at its outer end being rounded substantially on the arc 60 of a circle as clearly shown in Figures 1 and 2. The thumb stall 3 is formed from a single leather blank stitched to provide the stall and the base of the stall is set into an opening in the wrist portion of the palm section 2, as is usual and as illustrated in Figures 1 and 2.

In carrying out the invention, arcuate incisions 5 of the extent of approximately three-quarters of a circle, are made in the palm section 2 of the mitten end, in the instance of the left-hand mitten, are distributed in any desired manner over substantially the entire surface of the said palm section, as clearly shown in Figure 1 of the drawing. The formation of these incisions provides small flaps 6 which are of substantially the form of three-quarters of a circle and when these flaps are folded back as illustrated in the drawings, openings 7 will be provided for the purpose of ventilation. Preferably, the flaps are turned over in the direction of the wrist end of the mitten so that when the mitten is employed in the husking operation the margins of the flaps will engage against the husks rather than the folds formed in folding back the said flaps. The flaps are secured in their folded back position by means of tubular rivets indicated by the numeral 8, these rivets being 95 of the ordinary form and each having a flat smooth head 9 at one end of its tubular shank 10, and the end of the shank being split longitudinally and riveted down so as to provide, as usual, in the employment of such rivets, a number of radial portions indicated by the numeral 11. The rivets are secured through the flaps 6 and through the palm section 2 of the mitten and the rivets are so arranged that their flat smooth heads 9 will be located at the inner surface of the said palm section 2 so as to avoid any irritation of the palm of the wearer of the mitten. On the other hand, the roughened or 100 projecting outer ends of the shanks of the

105

110

rivets comprising the radial portions 11, are located at the outer surfaces of the respective flaps 6 and the said flaps and the said ends of the shanks of the rivets thereby constitute the roughening elements of the mitten. Like roughening elements are provided upon the inner side of the thumb stall 3 as clearly shown in Figure 1 of the drawings and are suitably distributed over the 10 surface of the said stall.

As previously stated, in the case of the left-hand mitten shown in Figure 1 of the drawings, the roughening elements are distributed substantially over the entire surface 15 of the palm of the mitten. However, in the instance of the right-hand mitten shown in Figure 2, the roughening elements are distributed only over the upper half of the palm, and the lower half of the palm is 20 left smooth, as is also the thumb stall, the reason for this difference in arrangement of the roughening elements being that the handle of the husking hook is grasped in the right hand and it would be inconvenient to 25 have the handle engaged by the roughening elements, as would be the case if the said elements were distributed over substantially the entire surface of the palm of the mitten, as in Figure 1.

It is preferable that the mitten, in both the right and left hand forms, be provided with 30 wristlets indicated by the numeral 12.

From the foregoing description of the invention it will be seen that there is provided 35 a husking mitten in which the roughening elements embody portions of the palm section of the mitten which are turned back and are secured by rivets which likewise constitute a part of each roughening element. 40 As stated, the rivets are of the ordinary type and may be purchased on the open market at an extremely low cost thereby materially reducing the cost of manufacture of the mitten as compared with that of the ordinary types 45 of mittens. It will likewise be evident that by forming the flaps 6 and turning them back to constitute protuberances or roughening elements, ventilating openings are provided in the palm section and thumb stall of 50 the mitten so as to provide for thorough ventilation of the interior of the mitten and prevent overheating of the hand to which it is applied and likewise alleviating perspiration and irritation incident thereto.

In order to further provide for ventilation 55 and particularly for the back of the hand, the back section 1 of the mitten is formed

with a number of ventilating openings indicated by the numeral 13, these openings being located and distributed in any manner found desirable and being likewise of any desired number. 60

Having thus described the invention, what is claimed as new is:

1. A husking mitten having roughening 65 protuberances comprising flap portions cut out from the material constituting the working side of the mitten and integrally connected therewith and folded back upon the outer face of the said side, and means 70 securing the said flap portions in their folded back position.

2. A husking mitten having roughening 75 protuberances comprising flap portions cut out from the material constituting the working side of the mitten and integrally connected therewith and folded back upon the outer face of the said side in the direction of the wrist end of the mitten, thereby providing 80 ventilating openings and means securing the flap portions in their folded back position.

3. A husking mitten having roughening 85 protuberances comprising flap portions cut out from the material constituting the working side of the mitten and integrally connected therewith and folded back upon the outer face of the said side and distributed over the surface thereof, and rivets secured 90 through the said side of the mitten and through the said flap portions and securing the said flap portions in their folded back position and at their outer ends constituting 95 protecting and roughening means for the said flap portions.

4. A husking mitten having roughening 100 protuberances comprising flap portions cut out from the material constituting the working side of the mitten and integrally connected therewith and folded back upon the outer face of the said side and distributed over the surface thereof, and rivets secured 105 through the said side of the mitten and through the said flap portions and securing the said flap portions in their folded 110 back position and at their outer ends constituting protecting and roughening means for the said flap portions, the inner ends of the rivet shanks having smooth flap heads engaging the inner surface of the said side of the mitten.

In testimony whereof I affix my signature.

HIRAM FRITZEN. [L. S.]
